UNITED STATES PATENT OFFICE

MORRIS MANN, OF BROOKLYN, NEW YORK

DESIGN FOR A BEADED SHOE BUCKLE OR SIMILAR ARTICLE

Application filed October 4, 1929. Serial No. 32,944. Term of patent 3½ years.

To all whom it may concern:

Be it known that I, MORRIS MANN, a citizen of the United States, and a resident of the borough of Brooklyn, county of Kings, city and State of New York, have invented a new, original, and ornamental Design for a Beaded Shoe Buckle or Similar Article, of which the following is a specification, reference being had to the accompanying drawing, forming a part thereof.

Fig. 1 of said drawing is a front elevation view of a beaded shoe buckle, showing my new design.

Fig. 2 is a top outline of a beaded shoe buckle, showing my new design.

I claim:

The ornamental design for a beaded shoe buckle or similar article as shown.

MORRIS MANN.
